UNITED STATES PATENT OFFICE

JACOB BERLINGER, OF BROOKLYN, NEW YORK

DESIGN FOR A FINGER RING OR SIMILAR ARTICLE

Application filed April 3, 1931. Serial No. 39,360. Term of patent 14 years.

To all whom it may concern:

Be it known that JACOB BERLINGER, citizen of the United States, and resident of Brooklyn, in the county of Kings and State of New York, has invented a new, original, and ornamental Design for Finger Ring or Similar Article, of which the following is a specification, reference being had to the accompanying drawings, forming part thereof, in which—

Fig. 1 is a side edge view of a finger ring embodying my new design;

Fig. 2 is a top end edge view; and

Fig. 3 is a developed view thereof.

I claim:

The ornamental design for a finger ring or similar article, substantially as shown.

Dated, New York city, March 26, 1931.

JACOB BERLINGER.
